UNITED STATES PATENT OFFICE.

SEVERIN JOHANSEN, OF ATLANTA, GEORGIA.

AUTOMATIC MECHANISM FOR TRAMPER BALING-PRESSES.

1,210,324.

Specification of Letters Patent. Patented Dec. 26, 1916.

Application filed March 7, 1916. Serial No. 82,742.

To all whom it may concern:

Be it known that I, SEVERIN JOHANSEN, a citizen of the United States, residing at Atlanta, in the county of Fulton and State of Georgia, have invented new and useful Improvements in Automatic Mechanisms for Tramper Baling-Presses, of which the following is a specification.

This invention relates to baling presses of the power tramper type particularly adapted for baling cotton and analogous products. In presses of this type the cotton is fed into the upper end of a press or baling chamber and is forced downwardly into said chamber by a tramping mechanism. In order that the parts may be automatic in their action provision is made in such presses whereby the cotton fed into the press box will upon a sufficient accumulation automatically operate mechanism for causing the tramper to descend and compactly press the cotton downwardly into the press box. The part which is directly acted upon by the accumulated cotton is usually in the form of a pivoted or movable apron or gate, which has been designated in some instances as a trip apron, there being suitable connections or devices operated by the movement of the apron under the influence of the accumulated cotton to open valves or actuate mechanical appliances for releasing or causing the tramper to descend, and the present invention has in contemplation the use of a pivoted or movable apron or gate against which the accumulated cotton may act, together with a novel form of valve mechanism including trip and restrictive devices as to movement of certain parts during the time that the tramper is resting at its maximum elevation; also when it has reached its lower limit of movement, and during its descent and ascent, the operation of the several coördinated devices and mechanisms being positive and automatic in their actuation.

The principal object of the invention is to provide mechanism in connection with a baling press of the type specified having a positive operation and automatic action and giving a free circulation of the pressure fluid medium between a pressure generating means and the tramper controlling means instead of passing said fluid pressure medium through a trap or release valve under maximum pressure, thereby reducing the power required to drive the pressure gener-

ating means to a minimum at such times when a maximum pressure is not necessary or desirable relatively to the fluid medium controlling the descent and ascent of the tramper.

The pressure generating or pump means used in connection with the improved baling press tramper mechanism may be of any preferred form and comprise any of the well known automatically operating pressure regulating accessories, and the pressure medium acting directly in the cylinder for operating the piston connected to the tramper stem may be either of a hydraulic nature, steam or any other analogous fluid capable of utilization for the same purpose. It will be readily appreciated that the provision of means for effecting a free circulation of the fluid medium between the pressure generating mechanism and the tramper controlling means with reduced power or pressure force will be materially advantageous in decreasing the strain on the several working parts, both of the pressure generating mechanism and the tramper controlling means, and, furthermore, such provision will also result in economizing in the power necessary to effectively operate the tramper controlling means and the baling of cotton or other material.

A preferred embodiment of the invention in its several phases is disclosed in the accompanying drawings and the practical organization thus illustrated will be herein-after described in detail as to its structure and operation.

In the drawings: Figure 1 is a perspective view of a portion of a baling box and a tramper mechanism embodying the features of the invention and showing the trip apron or gate partially broken away as well as the circulating pipes for the fluid medium, the tramper being in position of starting on its downward movement and the mechanism also disposed accordingly. Fig. 2 is a top plan view of the improved tramper controlling mechanism showing the cotton supply means or condenser and intermediate feed mechanism in connection therewith, parts of this view being broken away and illustrated in horizontal section. Fig. 3 is a transverse vertical section through the tramper controlling mechanism taken in the plane of the line 3—3, Fig. 1, and showing a portion of the cotton supply means and intermediate feeding devices. Fig. 4 is a longitudinal

vertical section taken in the plane of the line 4—4, Fig. 2. Fig. 5 is a detail transverse vertical section on an enlarged scale showing a portion of the bale box, strain rod and automatically operating means for controlling the valve operating mechanism, together with a portion of the swinging apron and trip lever all operating as a safety organization for preventing the valve mechanism from acting while the press box is being shifted when the strain rod is released from the box. Fig. 6 is a detail longitudinal section on an enlarged scale particularly showing the main valve operating mechanism and trip devices together with the means for preventing the valve operating mechanism from operating when the press box is in a certain position. Fig. 7 is a detail view in sectional elevation, partially broken away, particularly showing the release lever in full and dotted line positions and a two-way valve to control the circulation of the fluid pressure medium in accordance with the up and down movements of the trumper or platen member of the latter. Fig. 8 is a section through the valve shown in Fig. 7 taken at right angles to the section of the latter figure. Fig. 9 is a horizontal section through the valve shown by Figs. 7 and 8. Fig. 10 is a longitudinal vertical section of a four-way balance piston valve for controlling the inlet and exhaust of the fluid pressure medium relatively to opposite extremities of the trumper stem piston cylinder, the valve shown by this figure being adapted for liquid pressure medium. Fig. 11 is a similar view of the valve shown by Fig. 10 illustrating the valve as constructed for use with steam.

40 The numeral 5 designates a press box which is one of the usual double box constructions and having a swinging movement so that as one box is filled or has a sufficient quantity of cotton or other material pressed 45 thereinto it will be moved or swung from under the trumper mechanism and replaced by another similar empty box. Above the box suitable frame timbers or beams 6 are mounted and are spaced to form an opening 50 7 therebetween, these timbers operating to support the trumper mechanism and the devices coöperating therewith. On these timbers or frame beams 6 a trumper cylinder 8 is mounted in upright position and is constructed similarly to devices of this kind: 55 and slidingly mounted in the said cylinder is a rod or stem 9 which, as will be understood, is provided with a piston working within the cylinder and whereby pressure applied 60 to opposite points or at the upper and lower extremities of the cylinder will effect a reverse reciprocating movement of the said rod or stem 9. The rod or stem 9 moves through the open space between the timbers 65 or beams 6 and is attached at its lower end

to a follower block or platen 10 of such dimensions as to readily move downwardly into and upwardly through and from the press box 5. Depending from the front timber of beam 6 is a swinging gate or apron 11 having its lower edge normally adjacent or a short distance above the outer side edge of the press box 5, the gate or apron 11 having hanger arms 12 projecting from the upper portion thereof and provided with eye-plates which loosely engage and swing on outstanding hooks 14 secured to the said outer beam 6. The gate or apron 11 is in such position at all times as not to interfere with the movement of the follower block or platen 10 and operates as a trip means when the press box is filled with cotton or other material in a manner which will be more fully hereinafter explained. On the upper edge of the gate or apron 11 adjacent to one 80 of the hanger arms 12 is a metal contact plate 15 which is adapted to be engaged by retention or locking means at intervals.

Projecting upwardly from the top of the follower block or platen 10 is a trip bar 16 having upper and lower trip blocks 17 and 18 fixed to one side thereof. The trip bar 16 moves regularly with the upward and downward movements of the follower block or trumper 10, and at its upper end the trip block 17 has a contact projection 19 and the lower block 18 has an upper contact projection 20. The trip bar 16 is held in and moved through a guide 22 forming part of a clip or clamp 23 which is secured to the cylinder 8, as clearly shown by Figs. 1 and 2. The trip bar 16 has free movement in this guide but is retained against outward displacement therefrom by inturned ends of the guide, as at 24, see Fig. 2.

105 A pipe 25 connects with the head 26 of the cylinder 8, said pipe having therein a coupling 27 and also connected to one of the ports of a four-way controlling valve 28. A pipe 29 of smaller dimensions than the pipe 25 also connects with another port of the valve 28 and to the base 30 of the cylinder 8. The pipes 25 and 29 alternately operate as the conduit means for supplying and exhausting or liberating the pressure 110 medium, whether of liquid, steam or other gaseous form, relatively to the opposite extremities or the head 26 and base 30 of the cylinder 8. It will be understood that the greatest pressure on the follower block or platen 10 through the rod 9 must be exerted in a downward direction for the reason that such downward movement of the follower block or platen 10 must be forceful enough to effectively tramp the cotton and preliminarily press the same in the press box. Moreover, the pressure fluid of whatever character used should be admitted rapidly into the head 26 of the cylinder 8 to effect 115 a rapid as well as forceful downward move- 120

125 130

ment of the follower block or platen 10 and therefore the pipe 25 is of larger diameter than the pipe 29. The increased diameter of the pipe 25 also permits a rapid exhaust or relief of the pressure fluid from the upper part of the cylinder 8 when the follower block or platen 10 rises or ascends to normal position after performing its pressing function, and as there is no resistance on the follower block or platen 10 during its elevation except that in opposition to a body rising against force of gravitation, the pipe 29 of less diameter than the pipe 25 will feed or supply ample pressure fluid to the base 30 of the cylinder to rapidly elevate or cause an ascent of the follower block or platen 10. The pipe 29 like the pipe 25 also has a coupling 31 therein.

The four-way valve 28 for controlling the supply and exhaust of the pressure fluid medium to and from the cylinder 8 by way of the pipes 25 and 29 embodies a piston 32 having a stem or rod 33 projecting longitudinally through one end of the valve, this valve being shown in detail by Figs. 10 and 11 and more fully hereinafter particularly described. To the end of the valve 28 opposite that from which the piston rod 33 projects, an exhaust pipe 34 is connected, and to the bottom of the valve at an intermediate point another pipe 35 has attached communication and connects with a circulation controlling valve 36. The pipe 35 is connected to the valve 36 through the medium of a pipe 37 which runs to the pressure generator that may be of any suitable construction and constituting the supply conduit between the pressure generator and the valve 28 by way of the pipe 35. The circulation controlling valve 36 is of a two-way balanced piston valve type and is shown in detail by Figs. 7, 8 and 9, and at the point opposite to the attachment thereto of the pipe 37 a pipe 38 is connected and also runs back to the pressure generating medium. The pipes 37 and 38 with the valve 36 provide a circulating circuit for the pressure fluid medium under certain operative conditions of the improved trumper mechanism; and between the pipe 37 and the pipe 35 is a check valve 39 which has sufficient resistance to prevent the flow of the pressure fluid medium into the pipe 35 when communication is established through the valve 36 between the pipes 37 and 38 or at such times when the follower block or platen 10 has ascended to normal position and is in a state of rest during the intervals that the press box is being supplied with cotton or other material. It will be understood that the four-way valve 28 is a part of the circulating system but controls the feed of the fluid pressure medium to the trumper cylinder 8, and the circulation through the valve and the pipes 25 and

29 is only effective during the reverse movements of the follower block or platen 10 and its rod or stem 9. The exhaust pipe 34 from the valve 28 returns to the pressure generating medium or pump and gravity action 70 will be exerted thereon sufficient to insure a quick relief of the fluid pressure medium from either end of the trumper cylinder in accordance with the adjustment of the piston 32 in the valve 28 through the actuation of the piston rod 33, which will be hereinafter explained. The valve 36 also has a piston 39^a therein with a rod or stem 40 extending upwardly through the top of the valve, the said rod or stem projecting 75 below the bottom of the valve and having a spring 41 engaging the same and located within a cage or support 42 and whereby the tendency of the valve is to operate to a closed position. The upper end of the piston rod 40 of the valve 36 is connected to one end of an intermediately fulcrumed trip lever 43 arranged against the under side of the timbers 6 and having an adjustable tappet screw 44 in its free end in a position 80 to be struck by the top portion of the follower block or platen 10 when the latter rises to its full height.

Between the valves 28 and 36 and the trumper cylinder 8, follower block or platen 10 and trip bar 16, automatically operating mechanism of comparatively simple form is disposed to actuate the pistons 32 and 39^a of the said valves 28 and 36, and included in this mechanism is the trip lever 43 heretofore described and connected to the upper end of the piston rod 40 of the valve 36. Extending transversely across the timbers or beams 6 is a rockshaft 45 mounted in suitable bearings 46 and 47 and having upwardly projecting crank arms 48 and 49. The crank arm 48 is continuous with a depending rocking lever 50 provided with an outwardly deflected lower extremity 51 carrying a roller 52 which is so disposed as to ride over and rest upon the contact plate 15 of the gate or apron 11 and is released from said contact plate by the outward swinging movement of the gate or apron 11 caused by the cotton filling over the top of the press 100 box 5 and pressing against the said gate or apron, such movement of the gate or apron causing the upper edge thereof to swing outwardly and become displaced from beneath the roller 52 at the lower deflected end 105 51 of the rocking lever 50. The crank arm 48 is connected to the piston rod or stem 33 of the valve 28 by a bar or elongated link 53 which is pivoted at its opposite ends respectively to the said crank arm and the end 110 of the piston rod or stem 33. The crank arm 49 is connected to a spring shaft or rod 54, the said shaft or rod being pivotally engaged by the upper end of the arm 49 at a distance outwardly from the inner free end 115 55 of the rocking lever 50. The crank arm 49 is connected to the piston rod or stem 39^a of the valve 36 by a bar or elongated link 56 which is pivoted at its opposite ends respectively to the said crank arm and the end 120 of the piston rod or stem 39^a. The crank arm 49 is connected to a spring shaft or rod 57, the said shaft or rod being pivotally engaged by the upper end of the arm 49 at a distance outwardly from the inner free end 125 58 of the rocking lever 50. The crank arm 49 is connected to the piston rod or stem 39^a of the valve 36 by a bar or elongated link 58 which is pivoted at its opposite ends respectively to the said crank arm and the end 130 of the piston rod or stem 39^a. The crank arm 49 is connected to a spring shaft or rod 59, the said shaft or rod being pivotally engaged by the upper end of the arm 49 at a distance outwardly from the inner free end 135 59 of the rocking lever 50.

4

of said shaft or rod. The outer extremity of the shaft or rod 54 is engaged by a set 5 collar 55, and adjacent to the attached end of the arm 49 to said shaft a similar collar 56 is held on the shaft, and intermediately engaging and movable on the shaft is a sliding box 57. Between the collars 55 and 56 and the opposite ends of the sliding box the shaft or rod 54 has springs 58 and 59 thereon to exert a tension relatively to said shaft or rod in opposite directions. The outer end 10 of the shaft or rod 54 is reciprocatingly mounted in a fixed bearing or sleeve 60 held by a bracket 61 on a cross support 62 fixed to the timbers or beams 6 and bridging the space 7 between the latter. The sliding box 57 has a link 63 secured to the upper portion thereof and also to the upstanding elongated arm 64 of a trip bell-crank 65 provided with a shorter arm 66 normally standing approximately in a horizontal plane and terminating in a contact end 67. The fixed bearing or sleeve 60 has a slot extending into the lower portion thereof at about the 25 center of the same, as at 68, said slot being continued downwardly through the attaching member 69 of the bearing or sleeve, as at 69^a, and through the base of the bracket 61 and support 62 is an opening 62^a communicating with the space between the timbers or beams 6 and the opening 69^a.

Pivottally mounted on the base of the bracket 61, as shown in Figs. 5 and 6, is a lever cut-off or lock comprising a lever body 70 intermediately fulcrumed, as at 71, between upstanding ears 72 from the base of the bracket 61, a greater portion of the said lever body being in the form of a straight arm 73 on which a counterpoise weight 74 is adjustably mounted. The opposite end 35 of the lever body moves in the slot 68 continuing from the lower portion of the bearing downwardly through the attaching member 69 of the said bearing and terminates in a closure or cut-off plate or flattened terminal 75 which is so arranged as to close the bore of the bearing or sleeve 60 and limit the movement of the outer extremity of the shaft or rod 54 in the said bearing or sleeve. 40 The slot 68 heretofore specified as continuing through the base of the bracket 61 and the support 62 is in the form of an opening 76 in the latter devices, and depending from the lever body into the upper portion of 45 this opening is a lug 77 to which the upper end of a strain rod 78 is pivotally connected said rod having a loop or eye 79 at its lower end to engage a hook 80 on the adjacent end of the press box. When the eye 79 of the 50 strain rod 78 is in engagement with the hook 80 of the press box the outer extremity of the lever body 70 including the cut-off plate or closing member 75 is drawn downwardly so as to clear the closing plate from the bore 55 of the bearing 60, and when the lever body

is drawn into this position the weighted end at the rear is disposed horizontally and ready to act automatically when the strain rod eye 79 is released from the hook 80 to immediately cause the cut-off plate or closing member 75 to be thrown up into and across the bore of the bearing 60 and thus limit the outward movement of the shaft or rod 54 and serve as a safety lock at a time when the bale boxes are being shifted or 70 when a filled box has been released from the strain rod 78 and turned into position for completing the bale by other mechanism, and when the empty box has been thrown around into position the strain rod eye 79 is connected to a similar hook 80 thereon and the parts of the mechanism will then be free to perform their normal functions in regard to the operation of the trumper.

A safety attachment is used in coöperation with the shaft or rod 54 and consists of a trip dog 81 fulcrumed as at 82 to a depending portion of the clip or clamp 23 and having its upper edge disposed to engage the lower edge of one end of the guide 22. 85 The trip dog 81 has a weighted end 83 and a free extremity 84 which is normally held in contacting adjacency relatively to the shaft or rod 54 to operate as a cushion relatively to said shaft end and against the action of the compression springs 58 and 59 on the shaft. The free end 84 of the trip dog 81 is recessed or reduced, as at 85, to form a shoulder 86, the free end of the shaft or rod 54 being adapted to ride over the trip 90 dog into the recess 85 when the said dog is depressed during the descent of the follower block or platen 10, the dog and the shaft end remaining in this position until the follower block or platen ascends and a release is effected or the mechanism again set for an 95 automatic descent operation.

It is preferred that the valve 28, which is of the four-way type, be constructed as shown by Figs. 10 and 11, and the structure 100 of this valve as illustrated by Fig. 10 is to adapt the same for operation with a liquid pressure medium, the said valve embodying, as heretofore explained, a piston 32 with a projecting rod or stem 33 secured thereto 105 and whereby the piston may be shifted in the bore 87 longitudinally formed in the casing 88 and communicating fully at one end with an exhaust outlet or port 89 with which the pipe 34 communicates. The pipe 110 35 which intersects or is connected to the pipe 37 and attached to the bottom of the valve or casing 88 opens into a cross-way 90 located at about the transverse center of the casing 88, and within this casing are 115 other cross-ways 91 and 92 which are disposed at equal distances from the intermediate or central way 90 and have the pipes 25 and 29 communicating respectively therewith. The piston 32 is tubular or has an 120 125 130

opening or bore 93 extending fully therethrough from end to end, the said opening or bore 93 having an enlarged inlet 94 at the forward end of the piston or adjacent to the point where the rod or stem 33 is attached thereto. The piston 32 is intermediately reduced, as at 95, to provide an annular passage relatively to the wall of the bore 87 and whereby communication may be set up between the cross-way 90 and either of the ways 91 and 92, and as the valve is shown set in Fig. 10 the pipe 25 is opened by means of the cross-way 91 to the exhaust outlet 89 and pipe 34, and the pipe 29 is open to receive the pressure liquid from the pipe 35 through the cross-ways 90 and 92 and the annular passage between the latter ways provided through the bore 87 by the reduced portion 95 of the piston 32. It is obvious that a reverse position of the piston 32 will close the way 92 relatively to the way 90 and open said way 92 to the end or enlarged inlet 94 of the opening or bore 93 through the piston to exhaust through the pipe 29 and relieve the bottom of the cylinder 8 of pressure liquid and at the same time supply the upper end of said cylinder 8 with the pressure liquid in view of the fact that the cross-ways 90 and 91 will then be in communication through the bore 87 and which will be the position of the valve piston when the trumper follower block or platen 10 is forced downwardly or caused to descend. It will be seen that the piston rod or stem 33 slides through a suitable gland or analogous device 96 to provide a non-leakable joint, any preferred form of gland being used for this purpose. In Fig. 11 the valve 28 is substantially the same in structure as that shown by Fig. 10 and is adapted for use with steam, similar reference characters being applied to like parts, and the only essential difference in construction is that the piston 32 has a plurality of packing rings 97 therearound at opposite ends to avoid leakage, and in this instance also the bore 93^a is slightly changed in contour or is longitudinally straight without enlargement at the one end or other change of form, and it will be understood that either construction of bore 93 or 93^a may be used as desired.

The two-way valve 36 in addition to the features already described in connection with the piston 39^a thereof is provided with a suitable casing 98 having a vertical bore 99 extending fully therethrough and closed at the end by suitable cap glands 100. The bore 99 is intersected by cross-ways 101 and 102 respectively opening out through opposite sides of the casing, the pipe 37 having communication with the way 101 and the pipe 38 with the way 102, and the piston 39^a in this instance is intermediately reduced, as at 103, to set up communication between

the ways or to close the one way off from the other, as shown by Fig. 8. This valve 36 is supported by a suitable bracket 104 secured to the under part of the timbers or frame beams 6 and by this means the valve 36 is steadied in its operation, especially when the spring 41 within the cage 42 operates to force the piston 39^a up and close communication between the ways 101 and 102, and which is the position of the piston during the descent of the follower block or platen 10 into the press box, and at which time also the pressure medium is being fed through pipe 37 past the check valve 39 and by way of pipe 35 into the valve 28 and thence by pipe 25 to the top or head 26 of the cylinder 8. When the follower block or platen 10 rises or ascends to its full limit and engages the tappet screw 44 the piston 39^a is forced downwardly against the resistance of the spring 41 until the reduced portion of the piston 103 sets up communication between the ways 101 and 102, and at such time the pressure medium circulates through the pipe 37 and valve 36 to the pipe 38 and then back to the pressure generating medium, and at this time the press box may be filled with cotton or other material and the pressure medium is cut off from the top of the cylinder 8 in order to avoid any tendency to operate the trumper mechanism or cause a descent of the follower block or platen 10 during the filling operation. The check valve 39 operates at this time, or under these conditions, to hold up the trumper or platen by maintaining the pressure above the same against the lower portion of the piston in the cylinder 8 as a static column, the exhaust pipe 34 being cut off from communication, through the valve 28, with the bottom of the cylinder 8. To regulate the tension of the spring 41 in the cage 42 a tubular nut or adjusting device 105 is provided in the bottom of said cage, as clearly shown by Fig. 7, and the upward movement of the piston 39^a is limited by a collar 106 fixed to the lower end of said piston 39^a for contact with the upper end wall of the cage 42 which depends from the lower cap or gland inclosure 100.

As hereinbefore indicated, any suitable means may be provided for supplying the press boxes with cotton or other material to be pressed or packed therein, and as the device is particularly adapted for baling cotton or controlling the action of a cotton trumper, means are illustrated particularly in Figs. 2, 3 and 4 for controlling the supply of cotton to the press boxes at intervals, this particular supply controlling mechanism being omitted from Fig. 1 to avoid confusion in the illustration. The mechanism shown for controlling the supply of cotton to each press box embodies in the present instance a condenser or separator 107 which may be

of any approved type and has an outlet 108, as shown by Fig. 3, with suitable bat forming means 109 therein and consisting of a rotatable element 110 well known in the art and disposed on a shaft 111 having a drive gear 112 in mesh with a pinion 113 on a drive shaft 114 which may be operated by suitable power. The gear 112 and pinion 113 are of the bevel type, as shown by Fig. 2, and on the shaft 111 adjacent to the gear 112 is a sprocket wheel 115 with a sprocket or chain belt 116 trained thereover and over a sprocket wheel 117 on one end of a crank shaft 118, the sprocket wheel 117 being connected to and disengaged from the said shaft by means of a clutch 119 provided with a clutch shifting lever 120 depending to operating mechanism therefor as will be presently explained. The crank shaft 118 is held in suitable bearings secured on connecting frame members 121 extending from the rear timber or beam 6 upwardly to the adjacent side of the condenser or separator 107, and said shaft has an elongated crank 122 extending across a portion of the adjacent side of the condenser or separator 107 between the frame members 121. The chain belt 116 moves under the sprocket wheel 115 and engages a sprocket wheel 123 on a shaft 124 to actuate other mechanism within the condenser or separator 107. A fly wheel 122^a is secured on the end of the shaft 118 opposite that carrying the sprocket wheel 117, said fly wheel having a weight or counterpoise 122^b for a purpose hereinafter specified.

Suspended from the crank 122 is a feeder 125 consisting of an open or slotted frame of suitable length and provided with bearing clips 126 at its upper side to fit over the crank 122 adjacent to collars 127 fixed on the crank and holding the feeder 125 in fixed operating position relatively to the crank. To the bottom or lower side of the feeder 125 a feeder apron 128 is movably attached and comprises opposite side yielding straps 129 and a plurality of cross-slats 130, the opposite ends of the straps 129 being jointed to a support 131 secured to the under side of the rear timber or beam 6, as clearly shown by Fig. 3, said support 131 preferably being in the form of a transverse shaft or bar mounted in suitable bearings therefor. The jointed connections at opposite ends of the feeder apron 128 and the joints between the feeder 125 and the crank 122 permit the said feeder and apron to have free movement in response to the actuation thereof by the crank 122 of the shaft 118, and the feeder 125 is alternately caused to depress and rise or elevate and carries the feeder apron therewith.

Below the feeder 125 and apron 128 a chute or slide 132 is mounted and runs from a point below the outlet 108 of the condenser

or separator 107 downwardly and forwardly to a point over the rear side of the press box 5, the chute or slide 132 being fixed and having its lower end at such elevation above the press box that the latter may be readily shifted without engaging or jamming the said chute or slide. The cotton passes down from the outlet 108 of the condenser or separator onto the chute or slide 132, and during the operation of feeding the cotton to the press box over the chute or slide 132 the shaft 118 is regularly rotated and the crank 122 thereof is similarly rotated, thus vertically reciprocating the feeder 125 and causing the rear or upper edge of the apron 128 to pass downwardly behind the cotton delivered onto the chute or slide 132 and force the cotton downwardly and then forwardly over the open end of the press box 5. When the press box becomes full the cotton will be pushed straight across the top portion of the box and the cotton therein and will actuate the depending gate 11. The fly wheel 122^a performs the usual function of this class of devices relatively to maintaining a regularity of movement of the shaft 118, and the balance weight 122^b operates to hold up the flexible apron 128 to form a receptacle for the cotton fed from the condenser when the trumper or platen is descending in the bale 95 or press box.

The feeding mechanism or the devices just explained controlling the supply of cotton to the press box operates at intervals or when the press box is in position to be 100 filled, and the actuation of this mechanism or the supply devices is controlled by the clutch 119 through the clutch or shifting lever 120. This clutch or shifting lever 120 is intermediately fulcrumed, as at 133, see 105 Fig. 2, and the lower end thereof loosely engages an upstanding arm 134 of a bell crank lever 135 having a lower arm 136 extending through a slotted guide 137, as clearly shown by Figs. 2 and 4, the free end of the 110 lower arm 136 of this bell crank being supplied with a counterpoise weight 138 which is heavy enough to throw the clutch 119 in such manner as to connect the sprocket wheel 117 to the shaft 118 and thereby set up a 115 rotation of this shaft. Projecting upwardly from the top of the follower block or platen 10 close to the point where the trip bar 16 is secured to said block or platen is a vertical striker arm 139 so arranged that it will engage and elevate the inner free end of the lower arm 136 of the bell crank lever 135 and through the arm 134 of this lever and the shifting lever 120 the clutch 119 is thrown to connect the sprocket wheel 117 with the shaft 118 and thereby start the 120 feeder 125 and apron 128 and cause the cotton to be fed downwardly over the chute or slide 132 into the press box. The moment 125 that the press box is filled and the gate 11 130

has been forced outwardly, as shown by dotted lines in Fig. 3, by the overflow of cotton the follower block or platen 10 is caused to descend by mechanism hereinbefore explained and the arm 139 is released from engagement with the lower arm 136 of the bell crank 135, the weight 138 operating to bring the arm 136 of the bell crank downwardly with sufficient force to shift the clutch 119 through the lever 120 and bell crank arm 134 to disengage the sprocket wheel 117 from the shaft 118, and as soon as this disengagement ensues the said shaft 118 will cease to rotate and the crank 122 becomes inactive, the feeder 125 and apron 128 remaining in immovable position until the follower block or platen 10 again ascends to its full upper limit and the arm 139 engages the free weighted end of the arm 136 of the bell crank lever 135, when the feed of cotton over the chute or slide 132 will again ensue.

When the improved mechanism is set for the operation of filling the press box 5 thereunder the follower block or platen 10 is fully raised and the lever 43 has been operated through contact with the tappet screw 44 at the top of the follower block or platen 10 to shift the piston 39^a of the circulation controlling valve 36 to open up communication between the pipes 37 and 38 and whereby the pressure fluid medium circulates backwardly and forwardly through the pressure generating means and the said pressure fluid medium will not at this time pass upwardly through the pipe 35 to the valve 28 or will not have any circulation in view of the fact that the column of the pressure fluid medium will then be established through the pipe 35, valve 28 and pipe 29 and cylinder 8 to maintain the rod or stem 9 and the follower block or platen 10 in fully elevated position, and at such time the spring 58 on the shaft or rod 54 will be compressed by the slide sleeve or box 57 owing to the fact that the lower arm 66 of the bell crank 65 will have been engaged and elevated by the trip block 18 and the longer arm 64 of said bell crank will have been thrown over and exerted a pushing action on the link or connecting rod 63, and the inner end of the shaft or rod 54 will then rest in the recessed portion 85 of the trip dog 81, as shown by Fig. 6, and as a result the shaft 45 will be thrown over and the crank arms 48 and 49 carried therewith, the crank arm 48 thereby shifting the link or connecting rod 53 in an outward direction and correspondingly moving the piston rod or stem 33 and the piston 32. The lever 50 is also swung so as to bring the roller 52 at the lower end thereof in line with the upper surface of the wear or contact plate 15 on the upper edge of the gravitating gate 11, and this gate then swings inwardly or into normal position and causes an engage-

ment of the said roller 52 with the contact or wear plate 15 or upper edge of the gate, and the parts are thus held in set position until the press box is filled and overflows. The mechanism hereinbefore described for controlling the filling of the press box with cotton, for instance, is simultaneously set in operation when the follower block or platen 10 reaches its highest point of elevation through the action of the bell crank lever 135 which is engaged by the contact or trip arm 139 and the shifting lever 120 and by means of which the clutch 119 is thrown to set up a rotative engagement of the sprocket wheel 117 with the shaft 118. The moment that the shaft 118 starts to operate the cotton is fed or permitted to pass downwardly over the chute or slide 132 into the press or bale box 5, and when the cotton reaches the top of the said box and overflows it backs up against the gravitating gate 11 and forces the latter outwardly, thereby disengaging the roller 52 at the lower end of the lever 50 from the contact or wear plate 15 and releases the set mechanism controlling the actuation of the trumper and the spring 58 which has been compressed during the period of filling the press or bale box and said spring exerts a shifting movement on the shaft or rod 54 so as to actuate the crank arm 49 in an inward direction and correspondingly rock the shaft 45 and the arm 48, thereby shifting the piston 32 of the valve 28 so as to set up communication between the pipes 35 and 25 and open the exhaust through the valve 28 by way of the pipe 29 from the lower end of the cylinder 8 and immediately the follower block or platen 10 starts to descend and the piston 39^a of the valve 36 is automatically shifted by the spring 41 to close communication between the pipes 37 and 38 and whereby the pressure medium flows through the pipe 37 to and directly upward through the pipe 35. This reverse or inward movement of the shaft or rod 54 compresses the spring 59, and this is accomplished through the descent of the follower block or platen 10, trip bar 16 and trip block 17 which engages the arm 66 of the bell crank 65 and almost simultaneously the projection 19 of the said block 17 strikes the free end of the dog 81 and throws the same downwardly out of the way so that the shaft or rod 54 may move inwardly, it being understood that when the arm 66 of the bell crank lever 65 is depressed an inward pulling action will be set up on the slide sleeve 57 through the link or connecting rod 63 attached to the longer arm 64 of the said bell crank 65. This compression of the spring 59 is effected just as the follower block or platen 10 reaches its lowest stroke limit in the press or baling box 5 and immediately the compressed spring 59 exerts its

tension on the shaft or rod 54 to reverse the movement of the follower block or platen 10 the shaft 45 is rocked through the crank arm 49 attached to the shaft or rod 54 and the crank arm 48 moves inwardly 5 and draws on the link or connecting rod 53 and shifts the piston 32 of the valve 28 so as to shut off the feed of the pressure medium through the pipe 25 and open up this 10 pipe to the exhaust pipe 34 and at the same time establish feeding communication between the pipe 35 and the pipe 29, and by such disposition of parts the follower block or platen 10 is quickly elevated and when 15 it reaches the limit of its upward stroke the piston 39^a of the valve 36 is again shifted to open up communication between the pipes 37 and 38, and the automatic mechanism controlling the descent as well as the 20 elevation of the follower block or platen 10 is set for causing the said block or platen to descend at a proper interval or after the press or bale box is again filled and the roller 52 at the lower end of the lever 50 is 25 again brought into bearing with the contact or wear plate 15 by gravitation of the gate 11 to normal position.

It will be understood that when the follower block or platen 10 descends the feed 30 or supply of the cotton ceases as hereinbefore explained, but immediately the said block or platen rises the cotton is permitted to run or flow into the press or bale box. The trip block 18 resets the mechanism or 35 effects a compression of the spring 58 for subsequent descent of the follower block or platen 10 by engaging the under edge of the arm 66 of the bell crank lever 65 and correspondingly shifting the slide or box 57 on 40 the shaft or rod 54 and also operating the dog 81 to place the same in such position as to provide a safety means as well as a cushion 45 acting against the compression springs on the shaft or rod 54 and as shown by Fig. 1. As hereinbefore explained, when the 50 press or bale boxes 5 are shifting and the strain rod 78 is detached and attached to the successive boxes the cut-off comprising the plate or extended terminal 75 of the lever 55 55 70 will move into the bore of the bearing 60 to obviate the least movement of the shaft or rod 54 in an outward direction, and this automatic locking means will be restored to normal position when the strain rod 78 is 60 attached through the medium of the eye 79 at the lower end thereof with the hooks 80 65 on the successive boxes brought into position under the follower block or platen 10.

The improved mechanism also embodies 65 means for closing the lower end of the chute or slide 132 during the time that the follower block or platen 10 is depressed in the press or baling box 5, and in many structures a gate or closure element is fixed to the 70 follower block or platen for accomplishing

this occlusion of the lower end of the chute or slide 132. In the present instance, however, a gate 140 is secured to the follower block or platen 10 and is antifrictionally and slidingly mounted adjacent to the rear 75 timber or beam 6 and under control of the said follower block or platen and descending into and ascending above the press or bale box with the block or platen. When the gate 140 is lowered with the follower block 75 or platen it shuts off any cotton that may tend to flow over or fall from the end of the chute or slide 132. The gate 140 may be supported or held independently of the follower block or platen 10 by being mounted 80 to slide downwardly with the block or platen until the edge of the bale or press box is reached, when said gate will stop and close off the end of the slide or chute 132 and the block or platen continues to descend, and 85 when the block or platen rises and reaches the edge of the press box it picks up and raises the gate therewith to clear the end of the slide or chute 132 and permits the cotton to flow or fall into the press or baling box. 90

The circulation controlling or bypass valve 36 and the pressure medium controlling valve 28 together with the circulating pipes and the alternately acting feed and exhaust pipes between the valve 28 and the cylinder 8 will be embodied in a separate application and the valves particularly claimed or covered independently of the automatically operating mechanism between the valve 28 and the trumper organization. 100 The valves 28 and 36 are shown and described in this application to illustrate a full practical organization in accordance with the features of the invention, and said valves will be included in the appended claims 105 only in so far as to cover a complete combination of elements.

What is claimed is:

1. In operating mechanism for a trumper baling press including a baling box, a power cylinder having a reciprocating rod therein, a trumper block or platen secured to the said rod, a pressure medium circuit including a valve connected to the upper and lower ends of the cylinder and having an exhaust outlet and a longitudinally sliding piston to control the feed and exhaust of the pressure medium relatively to the said cylinder, a circulation controlling valve coöperating with the said valve connected to the cylinder, 110 automatically operating mechanism connected to the piston of said cylinder valve and actuated and set by the descent and ascent of the trumper block and platen, and automatically operating means for releasing said mechanism and the cylinder valve when the baling box is filled. 115

2. In operating mechanism for a trumper baling press including a baling box, a trumper including a pressure cylinder for caus- 120

ing the alternate descent and ascent of the trumper platen relatively to the baling box, a pressure medium circuit including a cylinder valve having communication with the 5 upper and lower portions of the said pressure cylinder and a circulation valve connected to and coöperating with the cylinder valve and pressure circuit for modifying the circulation of the pressure medium relatively to the cylinder valve, automatically operating mechanism connected to the cylinder valve for modifying the action of the latter, and means movable with the trumper platen to alternately release and set the said 10 mechanism.

3. In operating mechanism for a trumper baling press including a baling box, a trumper organization including a pressure cylinder operative for causing the alternate 20 descent and ascent of the trumper platen relatively to the baling box, a pressure medium circuit including a four-way valve with a piston and an exhaust outlet, the said valve being connected to the upper and 25 lower portions of the cylinder, pressure circulating means including an automatically operating valve connected to the said four-way valve for modifying the circulation of the pressure medium relatively to the latter, 30 valve, and means movable with the trumper platen to alternately release and set the said mechanism.

4. In operating mechanism for a trumper baling press, a trumper organization including 35 a pressure cylinder operative for causing the alternate descent and ascent of the trumper platen relatively to a baling box, a baling box disposed under the trumper organization, a gravitating gate suspended over the front portion of the baling box, a 40 pressure medium circuit including a valve connected to the upper and lower portions of the cylinder, and automatically operating mechanism connected to the valve for modifying the action of the latter and including 45 release means engaging the upper portion of the gate, said release means being thrown out of engagement with the gate by the pressure of the overflow cotton in the baling 50 box.

5. In an automatic mechanism for a trumper baling press, a trumper organization including means for causing the alternate descent and ascent of the trumper 55 platen, a baling box mounted under the trumper organization, a gravitating gate depending over the front portion of the baling box and movable by the overflow cotton in the latter, and automatically 60 operating mechanism associated with the trumper organization for controlling the actuation of the latter and including a lock device to engage the upper portion of the gate to hold the said mechanism for instant 65 operation when the lock device is released

from the upper portion of the gate by the overflow of cotton in the baling box.

6. In an automatic mechanism for a trumper baling press, a trumper organization including a pressure cylinder for causing the alternate descent and ascent of the trumper platen relatively to a baling box, a pressure medium circuit including a valve connected to the upper and lower portions of the pressure cylinder, a baling box 70 mounted under the trumper organization, a gravitating gate depending over the front portion of the baling box and movable from a normal position by the overflow cotton in the box, automatically operating mechanism 75 connected to the said valve for modifying the action thereof and including a lock device to engage the upper end of the gate and hold the said mechanism set for operation, and means movable with the trumper 80 platen to alternately release and set the said mechanism.

7. In an automatic mechanism for a trumper baling press, a trumper organization including a pressure cylinder for causing the alternate descent and ascent of the trumper platen relatively to a baling box, a pressure medium circuit including a valve 90 connected to the upper and lower portions of the pressure cylinder, a baling box 95 mounted under the trumper organization, a gravitating gate depending over the front portion of the baling box and movable from a normal position by the overflow cotton in the box, and automatically operating mechanism connected to the said valve for modifying the action thereof and including a lock device to engage the upper edge of the gate and hold the said mechanism set for 100 operation.

8. In operating mechanism for a trumper baling press, a trumper organization including a pressure cylinder for causing the alternate descent and ascent of the trumper platen, a baling box disposed under the said 110 trumper organization, a pressure medium circuit including a cylinder controlling valve connected to the upper and lower portions of the pressure cylinder and a circulation controlling valve connected to the 115 cylinder controlling valve, means operable by the overflow of the baling box to liberate a part of the said mechanism and modify the action of the valve, and means movable with the trumper platen to control the actuation 120 of the said cylinder controlling valve.

9. In an automatic mechanism for a trumper baling press, a trumper organization including a pressure cylinder operable for causing the alternate descent and ascent 125 of the trumper platen, a baling box disposed under the said trumper organization, a pressure medium circuit including a cylinder controlling valve connected to the upper and lower portions of the pressure cylinder 130

and a circulation controlling valve connected to the said cylinder controlling valve, automatically operating mechanism connected to the valve for modifying the action of the latter and including a movable lock device, and means operable by the overflow of the baling box and engaged by the said lock device when the trumper platen is elevated to hold the said automatically operating mechanism in set condition.

10. In an automatic mechanism for a trumper baling press, a trumper organization including a pressure cylinder operable for causing the alternate descent and ascent of the trumper platen, a baling box disposed under the said trumper organization and having a swinging movement, a pressure medium circuit including a valve connected to the upper and lower portions of the cylinder, a bypass valve also included in the said pressure medium circuit and provided with shifting means for modifying the ways thereof, a baling press holding means to maintain the box against movement during the operation of the platen, automatically operating mechanism connected to the valve of the pressure medium circuit which in turn is connected to the upper and lower portions of the pressure cylinder for modifying the operation of said valve, a locking mechanism for preventing a movement of a part of the automatically operating mechanism when the said holding means for the press box is released, and means movable with the trumper platen for setting and releasing the said automatically operating mechanism and the shifting means for the bypass valve.

11. In an automatic mechanism for a trumper baling press, a trumper organization including a pressure cylinder operable for causing the alternate descent and ascent of the trumper platen, a baling box disposed under the said trumper organization, a pressure medium circuit including a valve connected to the upper and lower portions of the cylinder and also a bypass valve provided with shifting means for modifying the ways thereof, automatically operating mechanism connected to the valve for the cylinder to modify the action of said valve, and means movable with the trumper platen to control the actuation of the said valve connected to the cylinder and also the shifting means of the bypass valve.

12. In an automatic mechanism for a trumper baling press, a trumper organization including a pressure cylinder operable for causing the alternate descent and ascent of the trumper platen, a baling box disposed under said trumper organization, a pressure medium circuit including a pressure medium supply control valve connected to the upper and lower portions of the cylinder, automatically operating mechanism connected to

said valve and having a trip device to hold the same in set condition, and means gravitatingly depending over the baling box and normally vertically disposed and movable by the overflow of the baling box, the said trip device engaging the means depending over the baling box when the latter is in normal condition to hold the said mechanism against movement during the filling of the box.

13. In an automatic mechanism for a trumper baling press, a trumper organization operable for causing the alternate descent and ascent of the trumper platen, a baling box disposed under said trumper organization, automatically operating mechanism for controlling the actuation of the trumper organization and including a trip means, and including means depending over the baling box and operable by the overflow of the latter, the trip means depending from the said automatically operating mechanism and loosely engaging and resting at intervals on the upper edge of the said gravitating means to maintain the said automatically operating mechanism in condition for immediate actuation when the trip means is released by the said gravitating means adjacent to the baling box.

14. In an automatic mechanism for a trumper baling press, a trumper organization operable for causing the alternate descent and ascent of the trumper platen, a baling box disposed and mounted to swing under the said trumper organization and to be replaced by a similar box, automatically operating mechanism connected to the trumper organization for controlling the actuation of the latter, a retention rod separably attached to the baling box, and an automatically operating safety lock mechanism connected to said rod and having a portion thereof movable into the path of operation of a part of said automatically operating mechanism to hold the latter against movement when the baling box is released and swung away and until replaced by another similar box.

15. In an automatic mechanism for a trumper baling press, a trumper organization including devices for causing the alternate descent and ascent of the trumper platen, a baling box disposed under said trumper organization, automatically operating mechanism associated with the said trumper organization and comprising a shiftable member engaged by opposed springs and means for alternately compressing said springs to effect reverse operations of the trumper organization, and means movable with the trumper platen for changing the position of the means for alternately compressing the said springs.

16. In an automatic mechanism for a trumper baling press, a trumper organiza-

tion including a pressure cylinder operable for causing the alternate descent and ascent of the trumper platen, a baling box disposed under said trumper organization, a pressure medium circuit including a valve connected to the upper and lower portions of the cylinder, automatically operating mechanism connected to said valve and comprising a shiftable member engaged by opposed springs and sliding means for alternately compressing said springs to effect reverse operations of the valve and trumper organization, and means movable with the trumper platen for engaging a portion of the said mechanism to alternately compress the said springs and set the mechanism in condition for reverse operations.

17. In an automatic mechanism for a trumper baling press, a trumper organization including a pressure cylinder operable for causing the alternate descent and ascent of the trumper platen, a baling box disposed under said trumper organization and mounted to swing and be replaced by another similar box, a pressure medium circuit including a cylinder controlling valve connected to the upper and lower portions of the cylinder and a circulation controlling valve connected to the cylinder controlling valve, automatically operating mechanism connected to said cylinder controlling valve to modify the action of the latter, mechanism for regularly feeding cotton into the baling box, and devices carried by the trumper platen and operable to control the actuation of the cotton feeding mechanism and the said automatically operating mechanism connected to the cylinder controlling valve, the cotton feeding mechanism auto-

matically ceasing to operate when the 40 trumper platen descends and instantly thrown into operation when the trumper platen ascends to its highest elevation.

18. In an automatic mechanism for a trumper baling press, a trumper organization operable for causing the alternate ascent and descent of the trumper platen, a baling box disposed under said trumper organization, automatically operating mechanism for controlling the actuation of the 45 trumper organization, a cotton supply means, a chute between said supply means and the top of the baling box, a crank shaft having a weighted balance wheel and operable from the cotton supply means, a flexible 50 apron movably attached to and actuated toward and from the chute to control the feed of cotton over the latter, the weight of the balance wheel operating to cause the flexible apron to form a receptacle to hold 55 the cotton against movement off the chute when the trumper platen is descending into the baling box, and mechanism interposed between and co-operating with the said crank shaft and the automatically operating 60 mechanism for controlling the actuation of the trumper organization to start and check the movement of the crank shaft when the trumper platen is above the top of the baling 65 box and when said platen is descending into 70 the box.

In testimony whereof I have hereunto set my hand in presence of two subscribing witnesses.

SEVERIN JOHANSEN.
